UNITED STATES PATENT OFFICE.

PETER KEIL, OF ELKHART, INDIANA, ASSIGNOR OF ONE-THIRD TO JOSEPH E. COCHRAN
AND ONE-THIRD TO E. A. STEPHENS, OF ELKHART, INDIANA.

MACHINE FOR LAPING BEARINGS.

1,076,636.

Specification of Letters Patent.

Patented Oct. 21, 1913

Application filed July 22, 1910. Serial No. 573,258.

To all whom it may concern:

Be it known that I, PETER KEIL, a citizen of the United States, residing at Elkhart, in the county of Elkhart and State of Indiana, have invented certain new and useful Improvements in Machines for Lapping Bearings, of which the following is a specification.

This invention relates to bearing lapping machines, and has for its general object to provide an improved construction, combination and arrangement of parts in a machine of this character.

One of the objects of this invention is to provide improved means whereby the lapping operation may be performed in a plurality of successive stages.

Another object is to provide improved means whereby the lapping operations may be performed within an emulsion of abrasive material so as to maintain an ever present supply of the emulsion between the lapping bars and the bearing surfaces of the bearings.

Other and further objects will appear in the specification and be specifically pointed out in the appended claims, reference being had to the accompanying drawings exemplifying the invention and in which—

Figure 1 is a side elevation of a machine constructed in accordance with the principles of this invention. Fig. 2 is a top plan view of the same. Fig. 3 is a section on the line III—III, Fig. 2. Fig. 4 is an enlarged detail fragmentary view of a portion of the machine shown in Fig. 3. Fig. 5 is a view from the right end of Fig. 4.

Referring more specifically to the drawings, and more especially to the embodiment of the invention shown therein, the bearing lapping machine is provided with a main base member or bed 1 rigidly mounted in any suitable manner, preferably on the legs 2. Rigidly secured upon the base member 1 by means of a plurality of bearing blocks 3, are a plurality of paired uprights 4, each pair of uprights being for the purpose of mounting an adjustable transverse frame 5 comprising oppositely disposed bearing blocks 5' slidably mounted on the uprights 4 and rigidly connected by an integral cross-bar 6. The frame 5 is maintained in adjusted position by the thumb screws 6', which are mounted in the blocks 5' and adapted when tightened to bind against the

uprights 4. The frame may be elevated or lowered so that bearings of different sizes may be lapped. In order to provide suitable means for holding a plurality of bearings against lateral displacement while they are having their bearing surfaces lapped, a transverse bar or support 7 is rigidly connected with the bearing blocks 5' by means of a pair of depending lugs 8 to which the support 7 is secured by means of screws or other suitable fastenings. The bed 1, uprights 4 and transverse frame comprising the blocks 5', cross bar 6 and support 7, form one of two relatively movable members, by the relative movement of which the lapping operations are accomplished. The movable member is provided by means of a table or movable support 9, which is reciprocably mounted upon the bed or base member 1 by having paired grooved rollers 10 rotatably mounted in bearing brackets 11, said rollers 10 being adapted to ride on a pair of V-shaped guides or rails 12 formed on the bed of the machine. In order to provide means for reciprocating the table 9 on the guide rails 12, a shaft 13 rotatably mounted upon the bed 1, preferably adjacent one end of said bed, is adapted to transmit power to a depending arm 14 rigidly secured to the under side of the table 9, by means of a crank arm 15 keyed to the shaft 13 and a connecting rod 16, which is pivotally connected at one end to the crank 15, and at the other end to the arm 14. A pulley 17 may be keyed to the shaft 13 to provide means whereby power may be delivered to the machine from a power shaft by means of a belt (not shown).

In order to provide simple and efficient means for maintaining an ever present supply of an abrasive emulsion between the bearing surfaces of the bearings to be lapped, and the lapping bars presently to be described, the reciprocating table 9, according to the present embodiment of the invention, has mounted thereon a pair of tanks or receptacles 18, each of said receptacles being provided with a pair of lugs 19, by means of which they may be clamped to the table 9, by means of clamps 20, which are secured to said table by means of bolts 21. Parallelly disposed within each tank 20 are a plurality of lapping bars 22, 23, 24, 25, 26, etc. These lapping bars are removably secured to the bottom of the tank or

lap box 20 by means of screws 28, so that when said lapping bars have become dulled by usage, they may be removed and reground. As shown best in Fig. 4, the lapping bars 22, 23, are preferably adapted to grind the sloping sides of the grooves, while the bars 24, 25 are adapted to grind the points of the grooves. Preferably, the four bars 22, 23, 24 and 25 are intended to rough 10 the bearing groove, while the bar 26 is intended to finish the points of the grooves, as well as the sloping sides thereof. With this method of operating the machine, as soon as the lapping bar 25 becomes dulled 15 by usage, the roughing operations may be performed by the bars 23, 24, 25 and 26, and the finishing operation given over to the additional bar 27, this plan being carried out until all of the lapping bars have been used. 20 As shown most clearly in Figs. 4 and 5, the transverse bar or support 7 is provided with a plurality of openings 29, which are disposed directly above the bars 22, 23, etc. The openings 29 are made of just the proper 25 size to receive the bearing 30, which may be of agate, or any other suitable material. In order to provide means for maintaining a uniform pressure between the bearing 30 and the lapping block 22, the cross-bar 6 30 has reciprocably mounted therein a plurality of plunger rods 31 provided on their lower ends with balls 32, adapting them to bear against the bearing 30. Preferably, said plungers 31 are forced against the bearing 35 30 by means of a spiral spring 33 interposed between the cross-bar 6 and each ball 32. As shown in Fig. 5, each plunger 31 has pivotally connected thereto at its upper end a shifting lever 34, which is pivoted 40 intermediately of its ends at 35 in a projection 36 on the cross-bar 6.

What I claim is:

1. A machine for lapping bearings which comprises a lapping member, a pressure member yieldingly holding the bearing in lapping continuous contact with said lapping member, and means for imparting relative reciprocating movement to said lapping member and bearing.
2. In a machine for lapping bearings, the combination of a stationary member and a movable reciprocating member, a lapping device mounted on one member, means carried by the other member adapted to hold a bearing against lateral displacement, and means resiliently mounted on said other member for pressing the bearing continuously against the lapping device.
3. In a machine for lapping bearings, the combination of stationary and reciprocally movable supports, a bath of lapping emulsion, a lapping device carried by one of said supports and having its lapping surface immersed in said bath, and a pressure

device carried by the other support adapted to automatically maintain a bearing with its bearing face against the lapping surface of said lapping device.

4. In a machine for lapping bearings, the combination of stationary and movable supports, a bath of lapping emulsion, a lapping device carried by one of said supports and having its lapping surface immersed in said bath, a resiliently movable pressure device carried by the other support adapted to automatically hold a bearing with its bearing face against the lapping surface of said lapping device, and means for imparting reciprocating movement to said movable support and bearing.

5. In a machine for lapping bearings, the combination with a stationary member, a movable member reciprocably mounted on said stationary member, a bath of lapping emulsion carried by one of said members, a lapping bar mounted on one of said members with its lapping surface immersed in said lapping bath, and means mounted on the other of said members adapted to hold a bearing against lateral displacement during the relative movement of said members, and resilient means for pressing the bearing against said lapping bar.

6. In a machine for lapping bearings, the combination with a base member, of a table reciprocably mounted thereon, a lapping bar mounted upon said table, said bar being adapted to fit the bearing surface of the bearing, means rigidly mounted on said base member adapted to hold the bearing against lateral displacement, and means for pressing the bearing yieldingly against said lapping bar with a uniform pressure.

7. In a machine for lapping bearings, the combination with a stationary base member, of a table reciprocably mounted thereon, a plurality of lapping bars mounted on said table longitudinally of the reciprocable movement of the table, a container for lapping emulsion surrounding the said lapping bars and adapted to contain a bath immersing said bars, a transverse support rigidly mounted on said base member and adapted to hold a bearing above each lapping bar, and means connected with said transverse support for pressing the bearings against said lapping bars.

8. In a machine for lapping bearings, the combination with a base member, of a transverse frame rigidly mounted thereon, a support carried by said frame, said support being provided with a plurality of openings each adapted to receive a bearing member, a reciprocably movable table mounted on the base member, a plurality of lapping bars secured to said table, said bars being disposed respectively under the openings in said transverse support, and a plurality of

plungers reciprocably mounted in the transverse frame above said openings in said support, said plungers being adapted to press the bearings against the lapping bars.

9. In a machine for lapping bearings, the combination with a base member, of a transverse frame rigidly mounted thereon, a support carried by said frame, said support being provided with a plurality of openings each adapted to receive a bearing member, and a plurality of plungers reciprocably mounted in the transverse frame above said openings in said support, said plungers being adapted to press the bearings against the lapping bars, said lapping bars being suitably formed to lap different portions of the bearing surface of the bearings.

10. In a machine for lapping bearings, the combination with a reciprocable table, a plurality of lapping bars parallelly disposed thereon, a rigidly mounted support extending transversely of said bars, and provided with an opening above each bar for the reception of a bearing to be lapped, and a reciprocable plunger mounted above each opening in said support and adapted to press the bearing against the lapping bar.

11. In a machine for lapping bearings, the combination with a reciprocable table, a plurality of lapping bars parallelly disposed thereon, a rigidly mounted support extending transversely of said bars and provided with an opening above each bar for the reception of a bearing to be lapped, and a reciprocable plunger mounted above said opening in said support and adapted to press the bearing against the lapping bar, said lapping bars being detachably secured to the table.

12. A machine of the class described, a traveling bearing grinder, in combination with an adjustable bearing-holder, adapted to automatically tension the bearing into continuous grinding engagement with the grinder.

13. A machine of the class described, comprising a moving platen and a grinding tool carried thereby, in combination with a bearing holder arranged to present the bearing to be ground continuously to the moving tool, and mechanism automatically compensating for the wearing and grinding away of the bearing and tool.

14. A machine of the class described, comprising a moving platen and grinding tools carried thereby, in combination with a vertically adjustable resilient bearing-holder arranged to present bearings of different sizes to be ground to the moving tool, and

mechanism automatically compensating for the wearing and grinding away of the tool.

15. A multiple grinder comprising a plurality of moving grinders, in combination with a vertically adjustable multiple work-holder, comprising a plurality of resilient work holding members, each arranged to automatically compensate for the wearing away of the work and the grinder.

16. In a machine for lapping bearings, the combination with a base member, of a transverse frame adjustably mounted thereon, a support carried on said frame, said support being provided with a plurality of openings each adapted to receive a bearing member, a reciprocally movable table mounted on the base member, and having a plurality of lapping bars secured thereto, said bars being disposed in alinement with the openings in the transverse support, and a plurality of plungers reciprocably mounted in the transverse frame above said openings in the support, said plungers being adapted to tension the bearings toward the lapping bars.

17. In a machine for lapping bearings, the combination with a stationary base member, of a table reciprocably mounted thereon, a plurality of lapping bars mounted on said table longitudinally of the movement of the table, a plurality of uprights disposed on said base member, a transverse frame adjustably mounted on said uprights, a support carried by said frame, said support being provided with a plurality of openings each adapted to receive a bearing member and a plurality of plungers reciprocably mounted in said frame above said openings in said support, the said plungers being adapted to press the bearings against the lapping bars.

18. A multiple bearing grinder, comprising a plurality of graduated grinders, in combination with a plurality of independent bearing holders, each adapted to present a bearing to a corresponding grinder, automatic mechanism individual to each holder adapted to compensate for the wearing away of the bearing, and a common support for said holders.

In testimony whereof I have signed my name to this specification, in the presence of two subscribing witnesses, on this 19th day of July A. D. 1910.
